UNITED STATES PATENT OFFICE.

RICHARD W. HAMANN, OF ST. LOUIS, MISSOURI, ASSIGNOR TO EUGENE J. FEINER, OF ST. LOUIS, MISSOURI.

BOILER-FLUE CLEANER.

No. 884,818.

Specification of Letters Patent.

Patented April 14, 1908.

Application filed July 13, 1907. Serial No. 383,655.

To all whom it may concern:

Be it known that I, RICHARD W. HAMANN, a citizen of the United States, and resident of St. Louis, Missouri, have invented certain new and useful Improvements in Boiler-Flue Cleaners, of which the following is a specification, containing a full, clear, and exact description, reference being had to the accompanying drawings, forming a part hereof.

10 My invention relates to a boiler flue cleaner, my object being to construct a simple cleaning apparatus, which is located immediately to the rear of boiler, either inside or outside of the rear wall of the boiler setting, and which apparatus is utilized to direct jets of steam or compressed air into and through the boiler flues to remove all soot and the like from said flues.

To the above purposes, my invention consists in certain novel features of construction and arrangement of parts, which will be hereinafter more fully set forth, pointed out in the claims, and illustrated in the accompanying drawings, in which:

25 Figure 1 is a vertical section of the rear portion of a boiler, and showing my improved apparatus arranged in the rear wall of the boiler setting; Fig. 2 is an enlarged horizontal section taken on the line 2--2 of Fig. 1; 30 Fig. 3 is a perspective view of a housing in which the jet tubes of the cleaner operate; Fig. 4 is a perspective view of the forward end of one of the jet tubes I make use of in carrying out my invention.

35 Referring by numerals to the accompanying drawings:—1 designates the boiler, 2 the flues therein, and 3 the rear wall of the boiler setting.

40 4 designates a housing, preferably constructed of metal, in mating halves, and with a wide open mouth, which is arranged immediately to the rear of that portion of the boiler in which the boiler flues are located; and said housing, in the present instance, is 45 shown as being located in the rear wall 3 of the boiler setting, although a portion of said housing may be located inside or outside of said wall.

Formed in the rear portion of the housing 4 are the horizontally arranged bearings 5, in which is arranged for rotation a tube 6; and seated therein, within the housing 4, is a series of jet tubes 7, which extend forward through the housing 4, and have their for-

ward ends flattened, as designated by 8, in 55 order to discharge the air or steam in thin jets through the forward open end of the housing.

The outer end of the pipe 6 is arranged for rotation in a housing 9 located on the end of 60 a pipe 10, which leads from a suitable source of steam or compressed air supply, and fixed on the pipe 6 is an operating handle 11.

When an apparatus of my improved construction is installed and it is desired to clean 65 the boiler flues, the steam or compressed air is allowed to discharge through the pipe 10, and from thence said steam or air passes through the pipe 6 into and through the jet tube 7, and discharges from the flattened 70 nozzles on the forward ends thereof.

The operator by engaging the handle 11 rocks the shaft 6, and thus the forward ends of the jet tube 7 are alternately raised and lowered, and the jets of steam or air issuing 75 from the forward ends of said tubes are thrown into the rear ends of all of the boiler flues 2; and, as a result, the soot and like foreign matter is forcibly blown through said tubes into the breeching at the forward end 80 of the boiler, from whence it is carried into the stack.

Where a battery of boilers are located side by side, one of the housings 4 may be located to the rear of each boiler, and the pipe 6 may 85 be extended through the rear ends of all of the housings, and thus the flues in all the boilers may be simultaneously cleaned.

Where the housing of the cleaning apparatus is bricked into the rear wall, as shown in the present instance, the pipe 6 is extended to the side of the boiler setting; and said pipe is, therefore, rocked from the side of the boiler setting; but where the rear portion of the housing projects through the rear wall of the boiler setting, the operating handle will be positioned on the pipe immediately adjacent the projecting portion of said housing, and thus the apparatus will be operated from the rear of the boiler setting.

A flue cleaner of my improved construction is easily installed, is operated with ease, and the steam supply may be taken from the exhaust of an engine, thus utilizing steam which would otherwise go to waste.

I claim:

1. The combination with a boiler, of a transversely disposed supply pipe arranged

at the rear of the boiler, and a series of jet tubes leading from said supply pipe toward the flues of the boiler.

2. The combination with a boiler, of a transversely disposed pipe located immediately to the rear of the boiler and arranged to rock, and a series of jet tubes leading from said pipe and toward the flues of the boiler.

3. The combination with a boiler, of a transversely disposed pipe located immediately to the rear of the boiler and arranged to rock, a series of jet tubes leading from said pipe toward the flues of the boiler, and means whereby said pipe is rocked.

10 4. The combination with a boiler, of a transversely disposed pipe located immediately to the rear of the boiler and arranged to rock, a series of jet tubes leading from said pipe toward the flues of the boiler, and means whereby the said pipe is supplied with 20 fluid pressure.

15 5. The combination with a boiler, of a transversely disposed pipe located immediately to the rear of the boiler and arranged to rock, a series of jet tubes leading from 25

said pipe toward the flues of the boiler, means whereby the said pipe is supplied with fluid pressure, and means whereby said pipe is rocked.

6. The combination with a boiler and its setting, of a housing arranged in the rear wall of the boiler setting, a pipe passing transversely through said housing and arranged to rock therein, and a series of jet tubes fixed in the pipe within the housing. 35

7. The combination with a boiler and its setting, of a housing arranged in the rear of the boiler setting, a pipe passing transversely through said housing and arranged to rock therein, a series of jet tubes fixed to the pipe 40 within the housing, and means whereby the pipe is rocked.

In testimony whereof, I have signed my name to this specification, in presence of two subscribing witnesses.

RICHARD W. HAMANN.

Witnesses.

M. P. SMITH,
E. L. WALLACE.
